DESIGN FOR A SUNSHADE FOR BEACHES OR THE LIKE

Henry M. Roth, Troy, Ohio

Application November 16, 1933, Serial No. 49,759

Term of patent 14 years

To all whom it may concern:

Be it known, that I, HENRY M. ROTH, a citizen of the United States, residing at Troy, Miami County, Ohio, have invented a new, original, and ornamental Design for a Sun Shade for Beaches or the like, of which the following is a specification, reference being had to the accompanying drawing, forming a part hereof.

In the drawing, Fig. 1 is a perspective view of the beach sun shade embodying my new design. Fig. 2 is a side elevation, Fig. 3 is a front elevation, and Fig. 4 is a plan view thereof.

I claim:

The ornamental design for a sun shade for beaches or the like substantially as shown.

In testimony whereof, I have hereunto set my hand this 14th day of November, 1933.

HENRY M. ROTH.
